UNITED STATES PATENT OFFICE.

GEORGE NORWOOD, OF BOSTON, MASSACHUSETTS, AND JOSEPH J. ROSE,
OF CINCINNATI, OHIO, ASSIGNORS TO W. T. HAYDOCK, OF ST. LOUIS,
MISSOURI.

SPRING-CONNECTION FOR VEHICLES.

SPECIFICATION forming part of Letters Patent No. 444,526, dated January 13, 1891.

Application filed September 4, 1890. Serial No. 363,908. (No model.)

To all whom it may concern:

Be it known that we, GEORGE NORWOOD, a citizen of the United States, and a resident of the city of Boston, in the county of Suffolk and State of Massachusetts, and JOSEPH J. ROSE, a citizen of the United States, and a resident of the city of Cincinnati, in the county of Hamilton and State of Ohio, have invented 5 certain new and useful Improvements in Springs and their Connections, of which the following is a specification.

The several features of our invention and the various advantages resulting from their use, conjointly or otherwise, will be apparent 10 from the following description and claims:

In the accompanying drawings, making a part of this specification, and to which reference is hereby made, Figure 1 is a bottom view of the forward end of a side-bar road- 20 vehicle, showing our invention applied thereto, the front axle and wheels being omitted from this view, as their presence is unnecessary for the proper understanding of our invention. Fig. 2 is a vertical central section in 25 the line of the axis of the rod, whereby the spring is operated, and showing the spring and its adjacent end parts in section, while the aforementioned operating-rod is shown in elevation. Fig. 3 is an elevation of the right- 30 hand end of the devices shown in Fig. 2. Fig. 4 is an elevation of one side of the lever which is next to the coiled spring, and which operates to directly act upon the said spring. That side of this lever which is at the left- 35 hand in Fig. 2 is shown in this Fig. 4. Fig. 5 is a view of the opposite side of this lever—viz., that side of it which is at the right hand in Fig. 2 and next to the end lever, whereby the first-named lever is operated. Fig. 6 is an 40 elevation of that side of the end lever which is next to the lever which operates the spring. The other side of the lever shown in Fig. 6 is shown in Fig. 3 in connection with the adjacent side of the projection of the lever 45 shown in Fig. 5. Fig. 7 is an elevation of a portion of the peripheral surface of a modified form of the lever shown in Figs. 4 and 5. Fig. 8 is a view of the right-hand end of the devices shown in Fig. 7. Fig. 9 is a view of

the left-hand end of the lever shown in Fig. 5c 7. Fig. 10 is a view on one side of a modified form of the levers shown in Figs. 4, 5, 6, and 3. In Fig. 11 the left-hand figure is a peripheral elevation of the inner lever shown in Fig. 10, while the right-hand figure in Fig. 11 is a 55 peripheral elevation of that lever which is the exterior one in Fig. 10. The mode in which the spring is attached to the right-hand lever in Fig. 11 is illustrated by dotted lines. The mode in which the operating-shaft for 60 turning the lever fits the said lever is shown in said left-hand figure of Fig. 11 by dotted lines. Fig. 12 is a view of the opposite side of the last-named levers when united, which is opposite to that shown in Fig. 10. Fig. 13 65 is a view of the preferred form of device for holding the end lever in place upon the body of the vehicle.

A indicates the vehicle-body. The usual side sills B B are shown in the drawings. 70

A indicates the usual front end sill of the body.

C C are the customary and well-known side bars.

D is the head-block, to which the side bars 75 are connected in any suitable manner.

E indicates one of the many forms of fifth-wheel which may be employed.

E' indicates the place where the king-bolt 80 is located.

F indicates the coiled spring. The thickness of the rod of which this spring is composed and the number of convolutions of which the spring is composed will be varied according to the description of vehicle to 85 which our invention is applied and the amount of weight which the body is designed to support. One end of this coiled spring F is connected to and is preferably integral with a rod, as F'. This rod extends from the bottom of the vehicle at right angles to the axis of the spring, and is suitably attached at a convenient point. In the present instance the free end of this rod F' is attached at F² 90 to the end sill A. The free end of this spring 95 F is supported by and engages a lever G as follows: The lever G is of an annular form, and on the side next to the screw it is pro-

vided with a projection G' , which extends a short distance within the space present within and formed by the convolutions of the spring. Around this projection G' is a recess G^2 , and in this recess a portion of the last convolution of the spring is located. The end of the spring passes on and around the end of the shoulder G^3 , formed by the cutting away of an outer portion of the lever 5 G , as shown in Figs. 4 and 5. The direction in which the end of the spring extends around the said shoulder G^3 is shown by the arrows in Figs. 4 and 5. A lug or arm G^4 , rigidly attached to the lever G and preferably integral 10 therewith, projects from the periphery of the said lug and engages a corresponding lug or arm H^4 on the end lever H , substantially as shown in Fig. 3. This lever H is preferably provided with a recess H' , so that the end of 15 the spring which embraces the shoulder G^3 shall thus be prevented from touching and interfering with the independent rotation of the levers G H . Thus, if the said end of the spring shall project somewhat beyond that 20 side of the lever G which is at the right hand in Fig. 2, which projection may occur when the spring is subjected to a severe twist or a torsional strain, it will not come in contact with the lever H , and consequently cannot impede 25 the rotation of the latter. That side of this lever H which is at the right hand in Fig. 2 is provided with a projection whereby the axial extension H^2 and the periphery of the hub is provided with an annular groove H^3 for the reception of the device, which secures the hub in 30 position and prevents the lever from slipping laterally. The preferred form of device for thus holding the lever H in position is denominated in general by the letter I , (see Fig. 13,) and 35 consists as follows: The arch I' is provided at each end with an extension piece or lug I^2 . At one side of the arch these lugs are united by the cross-brace I^1 . Each lug is provided with a suitable opening, as I^3 , for the reception of 40 the securing bolt or screw. The inner edge I^5 of the arch I' is in cross-section substantially of a convex semicircular shape. The inner edge of the locking-piece I^6 is in cross-section 45 substantially of a convex semicircular form. The bottom of the locking-piece is preferably flat, and thus the better adapted to rest upon a portion of the bottom of the vehicle-body. The ends I^7 I^8 of the locking-piece are concavely curved in cross-section. 50 When the locking-piece is introduced into the lower portion of the spaces occupied by the arch, each concavely-curved end of the locking-piece will closely fit the convexly-curved adjacent inner surface of the arch. 55 In applying the holding device I the extension H^2 of the lever H is first introduced within the arch I and raised up until the inner surface of the arch I' enters and occupies the upper half of the recess H^3 of the 60 said extension I^2 . The locking-piece I^6 is now introduced into the lower or open end of the arch and elevated until its concave in-

ner surface I^5 enters the lower portion of the annular recess H^3 of the extension H^2 of the lever H , the ends of this locking device at 70 the same time interlocking with the respective adjacent lower portions of the arch. The holding device I thus combined with the lever H is now located upon the bottom of the vehicle-body, so that the bottom of the lugs 75 shall rest upon a suitable portion of the bottom of the vehicle-body. In practice the lug is preferably located upon the body-bottom brace J , which may extend parallel to the length of the body or transversely to the 80 length, as desired. The lugs I^2 of the holding device are now secured to the body A or brace J of the body by means of suitable bolts or screws K .

The rod M is provided at one end with the 85 arm M' , whose length is substantially at right angles to the length of the axis of the rod M . The free end of the arm M' or of the rod M is connected to the frame C D by a shackle N , of any of the appropriate well-known 90 forms and in any of the well-known ways. One description of such attachment is illustrated in the drawings, and consists of the clip N' , united to the frame and pivotally connected to one pivot-bolt of the shackle N , 95 the other pivot-bolt of the shackle being connected to the free end of the arm M' . A portion of the rod M , near to the arm M' , is journaled in a suitable bearing S , attached to the body of the vehicle by suitable screws 100 or bolts, as S' S' . That end of the rod M which is opposite to where the arm M' is connected passes through an opening G^5 in the lever G and also through an opening H^5 in the lever H . The opening G^5 in lever G is circular 105 in cross-section and of a diameter slightly larger than the diameter of the rod M , thereby enabling the rod M to turn easily within the lever G and without tapering the said lever when it (the said rod M) is rotated. That 110 portion of the rod M which is located within the opening H^5 of the lever H , is of an angular shape in cross-section, and the opening H^5 is of a like angular shape, and the rod M closely fits the opening H^5 in lever H . In this 115 way the rotary motion imparted to the rod M through the agency of the arm M' as the body A rises and falls is communicated to the lever H . Thus the rod M and the lever H are in operation substantially one and operate as if integral. The said rod M and said 120 lever H might, indeed, be integral were it not that economy in their manufacture compels them to be made in separate pieces. The rod M is prevented from slipping out of the lever 125 H in that direction which is toward the arm M' by means of a nut H^6 or equivalent suitable device. One form of such device is shown, and consists of the nut H^6 , screwed upon a screw-thread H^7 , located on the adjacent end of the rod M . Devices similar to those just described are located on the other side of the wagon-body, and a similar number of these devices are located at that por-

tion of the vehicle-body which is opposite to where the first-named number of devices are located. Thus the body is everywhere equally supported in an elastic manner.

5 In operation, as the weight is placed upon the body, the body descends, and that end of the arm M' which is connected to the torsion-rod M is lower in relation to that end of the said arm M' which is connected to the shackle. 10 N. The rod M is partially rotated. This partial rotation of the rod M operates to rotate the lever H. As the lever H rotates, its projection H⁴, impinging against the projection G⁴ of lever G, rotates the lever G. This last-named lever G, by means of its shoulder G³ bearing against the adjacent interlocking end of the spring F, rotates the spring F, and as the free end of the spring F is prevented from rotating by means of the arm F', secured to the vehicle- 15 body, the spring F is twisted, and thus its elasticity is developed. In this way the spring-power of the spring F is brought into action, and the body A rides easily and elastically by reason of the spring devices aforementioned. 20 The degree of elasticity obtained from the spring F may be varied by an adjustment, as follows: In the arm G⁴ of the lever G an interiorly-screw-threaded opening G⁶ is formed, and a screw G⁷ engages the screw-thread of the opening G⁶, (see Fig. 7,) 25 and as this screw G⁷ is screwed forward its inner end will impinge against the arm H⁴ of the lever H, and thus separate the arms H⁴ and G⁴, the inner end of the screw G⁷ thus being an extension of the arm G⁴. The farther the screw G⁷ is made to project beyond that face of the arm G⁴ which is next to the arm H⁴ the more severe will be the twist imparted to the spring F as the body descends 30 a given distance. By retracting the screw G⁷ the torsional rotation of the spring F is diminished, and its resilient power will be correspondingly lessened.

In Figs. 7, 8, and 9 there is shown a single lever in which the essential features of both levers G and H are combined. In that side of the lever which is at the right-hand side in Fig. 7 the groove G² for the reception of the end of the coiled spring is present. The shoulder G³, around which the free end of the coiled spring is bent, is also present. The extension G', which fits in the space formed by the convolutions of the spring, is also present, affixed to the right-hand end of the lever, as shown in Fig. 7. The axial extension H², which is supported by the holding device I or other suitable device, is affixed to that side of the lever G which is at the left hand in Fig. 7. An adjusting-screw G⁷, located in the outer peripheral extension of the lever, is present, and its inner end bears against that end of the spring which is bent across the shoulder G³. By advancing the screw G⁷ the torsional resistance of the spring F is increased, as hereinbefore mentioned, it being understood that the end of the rod M passes through the lever G, and is provided with an-

10 gular faces which engage corresponding angular faces on the inner surface of the opening H⁵ through the lever. That end of the opening H⁵ which is in the extension H² may, when preferred, be made of a round shape in cross-section. On that part H⁷ of the end of the rod M which projects beyond the free end of the extension H² is screwed a nut H⁶, 15 as already before mentioned.

In Figs. 10, 11, and 12 the lever G is united to the adjacent end of the spring F. (Shown in dotted lines, substantially as it is shown united in Figs. 1, 2, 3, 4, 5, and 6.) That side 20 of the lever G which is next to the lever H is recessed out, forming a recess G⁸, and the arm or abutment G⁴, which in Fig. 3 projects beyond the periphery of the lever, here is found present at the edge of the recess G⁸, 25 and the edges of that side of the lever H which is adjacent to the lever G are beveled away, thus enabling the lever H to enter and be located within the recess H⁸ of the lever H. The abutment or arm H⁴ on the periphery of the lever H will thus engage the abutment G⁴ of the lever G as the vehicle-body 30 descends and the arm M is rotated. In this illustrative instance the adjusting-screw G⁷ passes through the arm G⁴ and bears against 35 the abutments H⁴ of the lever H, and for the better enabling of the adjusting-screw to perform this function in a confined space the lever H is provided directly in front of the abutment G⁴ with a recess H⁹. This recess receives one side of the end of the adjusting-screw G⁷. That end of the torsion-rod M which engages with the lever H may be made to taper for a part of the way through the lever H. The opening in the lever H will be 40 similarly formed, as is indicated by dotted lines in Fig. 11. While in the present illustrative instance we have shown our invention as applied to a side-bar vehicle, we do not wish the application of our invention to 45 be confined to this particular class of vehicles, but wish it understood that our invention is to be applied to any other class or kind of vehicles to which it may be applicable.

115 While the various features of our invention are preferably employed together, one or more of the said features may be employed without the remainder, and in so far as applicable one or more of the said features may 120 be used in connection with spring devices of a description other than the one herein specifically set forth.

125 What we claim as new and of our invention, and desire to secure by Letters Patent, is—

1. In combination with a vehicle-gear, the spring F, secured at one end of the vehicle-body and at the other end to the lever G, having the shoulder G³, across which the terminal 130 end of the spring is bent, and the rod M, journaled in bearings S, provided with the lever-arm M', the rod M, passing through spring F and fixed to the device for rotating the

lever G as the arm M is rotated, the lever being provided with screw G⁷, arranged, substantially as described, for increasing or diminishing the torsional resistance of the spring F, substantially as and for the purposes specified.

2. In combination with a vehicle-gear, the spring F, secured at one end of the vehicle-body and at the other end to the lever G, having the shoulder G⁸, across which the terminal end of the spring is bent, and the rod M, journaled in bearing S and provided with the lever-arm M', the rod M passing through the spring F and fixed to the device for rotating the lever G as the arm M is rotated, and the holding device I, consisting of the arch I', provided with lugs I², and the locking-piece I⁶, whose ends are arranged to engage with the inner wall or surface of the arch, the holding device I being adapted to engage the extension H² of the lever device at the end of the spring, substantially as and for the purposes specified.

3. The spiral spring F, at one end secured to the vehicle-body, substantially as described, and at the other end engaging a lever G, this lever being provided with the extension G', entering the space formed by the convolutions of the spring, and being also provided with the annular recess G², into which the adjacent end of the spring enters, the lever being provided with the shoulder G³, across which the adjacent terminal portion of the spring is bent, arm G⁴, rigidly attached to the lever G, lever H, provided with arm H⁴, arranged to engage the arm G⁴ of the lever G, and the rod M, journaled in bearing S, passing loosely through the opening G⁵ of lever G and being rigidly fixed to the lever H, substantially as and for the purposes specified.

4. The spiral spring F, at one end secured to the vehicle-body, substantially as described, and at the other end engaging a lever G, this lever being provided with the extension G', entering the space formed by the convolutions of the spring, and being also provided with the annular recess G², into which the adjacent end of the spring enters, the lever being provided with the shoulder G³, across which the adjacent terminal portion of the spring is bent, arm G⁴, rigidly attached to the lever G, lever H, provided with arm H⁴, arranged to engage the arm G⁴ of the lever G, the rod M, journaled in bearing S, passing loosely through the opening G⁵ of lever G and being rigidly fixed to the lever H, the lever H being provided with the extension H², having the recess H³, and the holding device I, having arch I', securing-lugs I² I², and locking-piece I⁶, whose ends are arranged to respectively engage the respective adjacent sides of the arch I', substantially as and for the purposes specified.

5. The spiral spring F, at one end secured to the vehicle-body, substantially as described, and at the other end engaging a lever G, this lever being provided with the extension G',

entering the space formed by the convolutions of the spring, and being also provided with the annular recess G², into which the adjacent end of the spring enters, the lever being provided with the shoulder G³, across which the adjacent terminal portion of the spring is bent, arm G⁴, rigidly attached to the lever G, lever H, provided with arm H⁴, arranged to engage the arm G⁴ of the lever G, the rod M, journaled in bearing S, passing loosely through the opening G⁵ of lever G and being rigidly fixed to the lever H, the lever H being provided with extension H², having recess H³, and the holding device I, having arch I', securing-lugs I² I², locking-piece I⁶, whose ends are arranged to respectively engage the respective adjacent sides of the arch I', and nut H⁶, secured upon the end H⁷ of the rod M, substantially as and for the purposes specified.

6. The spiral spring F, at one end secured to the vehicle-body, substantially as described, and at the other end engaging a lever G, this lever being provided with the extension G', entering the space formed by the convolutions of the spring, and being also provided with the annular recess G², into which the adjacent end of the spring enters, the lever being provided with the shoulder G³, across which the adjacent terminal portion of the spring is bent, arm G⁴, rigidly attached to the lever G, lever H, provided with the arm H⁴, arranged to engage the arm G⁴ of the lever G, the rod M, journaled in bearing S, passing loosely through the opening G⁵ of the lever G and being rigidly fixed to the lever H, the lever H being provided with the extension H², having the recess H³, and the holding device I, having arch I', securing-lugs I² I², locking-piece I⁶, whose ends are arranged to respectively engage the respective adjacent sides of the arch I', and the adjusting-screw G⁷, screwed through the arm G⁴ of the lever G, substantially as and for the purposes specified.

7. In combination with a device for twisting the spiral spring and the end bearing for upholding the same, the device I for upholding the said bearing, consisting of the arch I', lugs I², and locking-piece I⁶, having its ends arranged to respectively engage the respective adjacent walls of the arch, the aforementioned bearing being received between the arch I' and the locking-piece I⁶, substantially as and for the purposes specified.

8. In combination with a vehicle-gear, the spring F, secured at one end to the vehicle-body and at the other end to the disk G, the latter being provided with groove in its side and shoulder on its periphery, the adjacent coil of the spring lying in the groove, and the adjacent terminal end of the spring being bent across the said peripheral shoulder, and the rod M, journaled in bearing S and provided with the lever-arm M', the rod M passing through the spring F and fixed to the disk G, substantially as and for the purposes specified.

9. The four separate and independent levers, located, respectively, at their respective corners of the vehicle, and each consisting of a rod M, having a lever-arm M', the free end 5 of the latter being connected to the vehicle gear-frame, the rod M, journaled in bearings fixed to the vehicle-body, each rod being provided with a coiled spring embracing the said rod and secured at one end to the vehicle- 10 body and at the other end to a discal piece G, having a peripheral shoulder, around which

the adjacent terminal end of the spring is bent, the rod M passing through the discal piece and provided with device for rotating the discal piece, substantially as and for the 15 purposes specified.

GEORGE NORWOOD.
